ELECTRICAL MUSICAL INSTRUMENT WITH
SPLIT KEYBOARDNicholas Langer, New York, N. Y., assignor to
Central Commercial Company, Chicago, Ill., a
corporation of Illinois

Application January 31, 1948, Serial No. 5,573

8 Claims. (Cl. 84—1.17)

1

This invention relates to electronic musical instruments, and, more particularly, to electronic organs in which a playing manual is split into two portions, each of which is assigned to the playing of musical notes of different tone color.

In present electronic organs generally a plurality of playing manuals or keyboards and a pedal keyboard are provided, capable of being actuated by an operator in accordance with the requirements of a musical composition. In general, a separate tone quality or tone color control is provided for each manual and also for the pedal keyboard so that the tone color of the notes produced upon playing each manual and also the pedal keyboard may be individually and independently adjusted. Thus, one or several notes may be played on one of the manuals with the one hand and with a desired tone color or combination of tone colors, other selected notes may be played on the other of the manuals with the other hand with other desired tone colors, and further selected notes may be played on the pedal keyboard by the feet with further selected tone colors. In this manner, it is possible to play a complex musical composition in such a way that the several "voices" forming the composition will be heard with different and desired tone colors thereby producing pleasing musical effects comparable to those obtainable by the musical ensemble composed of several orchestral instruments of different type, such as strings, flutes and reeds.

In smaller and less expensive organs only a single manual keyboard is provided, usually one having a range of five octaves or 61 notes, together with a pedal keyboard, although the latter may be omitted in some cases to further reduce the cost of the instrument. In organs of this type, in order to retain to some extent the possibility of playing "voices" of different tone color with each hand, an arrangement denoted by the organ term "split keyboard" is employed. In the "split keyboard" arrangement, the keys of the keyboard are separated or divided into two portions at a convenient point, and a separate tone quality or tone color control is provided for each portion. The point of division may vary somewhat with different organs but it is always fixed and is generally so determined as to provide a greater range, for example 3 octaves (37 notes), or more, for the right hand; which usually plays the leading "voice" or melody, and to provide a lesser range, for example 2 octaves (24 notes), or less, for the left hand, playing the accompaniment.

2

While this conventional "split" keyboard arrangement provided substantial savings in space and equipment and was in general use in small pipe organs and reed organs, its employment was the source of various operating difficulties and disadvantages and imposed serious musical limitations upon the instrument. Thus, the musical range of which each portion was capable was at best quite limited. When, for example, 5 the upper portion of the keyboard, playing the melody, was assigned to the production of a string or flute quality and the lower portion of the keyboard, playing the accompaniment, was assigned to the production of a reed quality, it frequently occurred that one or both portions had a range which was insufficient for playing certain musical compositions. Thus, when the frequency range of the accompaniment extended upwards beyond two octaves or that of the melody extended downwards beyond three octaves (that is beyond the point at which the keyboard was "split"), certain notes of the melody "voice" would sound with the tone color assigned to the accompaniment, and certain notes of the accompaniment 10 would sound with the tone color assigned to the melody. Of course, this was extremely disconcerting both to the player as well as to the musically trained listener. In certain cases some relief was obtained by transposing the composition into a different key but this was predicated upon transcribing the original composition with great trouble and frequently resulted in a key which was quite difficult to play. Also, even this rather troublesome expedient frequently failed 15 to produce the desired results. Although this problem inseparably connected with the operation of conventional organs of the "split" keyboard type was well known to those skilled in the art for many years and considerable thought was 20 devoted to its solution, none, as far as I am aware, of the suggestions and proposals made in this direction was completely satisfactory and successful.

I have discovered that the problem may be 25 solved in a remarkably simple manner.

It is an object of the present invention to provide an organ of the "split" keyboard type which eliminates the disadvantages and inconveniences connected with conventional organs embodying 30 the usual "split" keyboard feature.

It is another object of the present invention to provide an organ, more particularly an electronic organ, of the "split" keyboard type in which the point where the keyboard is divided or "split" into 35 two portions, assignable to different tone qualities

or tone colors, is not fixed but is adjustable and capable of being preset in a manner most suited to the requirements of a particular musical composition.

It is a further object of the invention to provide a single manual electronic organ equipped with means for "splitting" the keyboard into two sections, independent as regards setting up desired tone qualities, the said means being conveniently arranged and instantaneously actuatable by the player to an extent that the point where the keyboard is "split" may be shifted or displaced even while playing a musical composition.

It is also within the contemplation of the present invention to provide an electronic organ of the character described having an instantaneously adjustable keyboard "splitting" system incorporated therein which is capable of being preset to any desired point within a specific range, for example within one octave, of the range of the instrument.

The invention also contemplates a "split" keyboard system with adjustable "splitting" point for electronic organs of the single manual type which is extremely simple in character, reliable in operation and which may be readily installed in existing electronic organs or incorporated into new electronic organs of advanced design at a low cost.

Other and further objects and advantages of the invention will become apparent from the following description, taken in conjunction with the accompanying drawings; in which

Fig. 1 illustrates the schematic circuit diagram of a single manual electronic organ embodying the present invention;

Fig. 2 depicts the circuit of a preferred quality control or filter employed in the organ of the invention, producing a tone color simulative of a string instrument;

Fig. 3 shows the circuit of a similar filter, producing a tone color simulative of a flute;

Fig. 4 is the circuit of another similar filter, producing a tone color simulative of a reed instrument;

Fig. 5 is a side elevational view, somewhat diagrammatic and fragmentary in character of a push button switch of the type that is preferred for the purposes of the invention; and

Fig. 6 is a perspective view, also fragmentary, of a keyboard with quality control tablets or stops and with conveniently arranged push buttons for adjusting the point of "splitting" the keyboard into two independent portions.

Referring now more particularly to Fig. 1 of the drawings, there is shown therein the circuit organization of a single-manual electronic organ embodying the principles of the present invention. Reference characters H-1 to H-36 denote a plurality of generators of electrical oscillations having frequencies corresponding to those of musical notes within five octaves of the equally tempered scale, it being understood, however, that a lesser or greater number of octaves may be used. For convenience of illustration only the generators corresponding to the three lowest octaves have been shown and only the generators of the lowest and of the highest frequency in the last two octaves. Also, in each of the three octaves only the generators corresponding to the "natural" notes (C, D, E, F, G, A and B) have been illustrated although in a practical organ twelve notes including also the so-called "sharps" (that is C#, D#, F#, G# and A#) are included in each octave, in accordance with the twelve

notes of the equally tempered scale, now almost universally employed in all keyboard instruments.

The generators or alternating voltage sources 5 may be of any suitable type such as vacuum tube oscillators of the feed-back or of the relaxation type, gas-discharge tube oscillators, electrostatic and electromagnetic generators employing elements movable with respect to each other, generators employing photo cells and movable waveform scanners, etc. In this connection, reference is made to the following United States

10 patents: Cahill Patent 1,295,691; Langer Patent 1,832,402, Firestone Re. Patent 21,137, and Potter Patent 1,678,872. Among the generators which 15 are particularly suitable for carrying the principles of the present invention into practice may be further mentioned the cascaded harmonically related multi-vibrators disclosed in the Larsen 20 Patent 2,403,090 and in the Larsen et al. Patent 2,410,883, and the aperiodic frequency dividing networks of the type disclosed in my co-pending application Serial No. 625,018, filed October 27, 1945.

25 The switching arms of key switches S-1 to S-36 are adapted to cooperate with stationary contacts T-1 to T-36, respectively, contact being made upon depression of the corresponding playing key of the manual. Stationary contacts 30 T-1 to T-36 are respectively connected to output terminals U-1 to U-36. Of these, terminals U-1 to U-12 are connected to a common output bus bar #2, while terminals U-13 to U-36 are connected to another common output bus 35 bar #3.

As to terminals U-7 to U-16, which are 40 respectively connected to stationary contacts T-7 to T-16 of keying switches S-7 to S-16, adjoining pairs thereof are electrically connected to each other by means of keyboard splitting switches K-1 to K-9, these switches being 45 normally closed and being capable of selective actuation by depression of push buttons L-1 to L-9, respectively, one of which is coordinated to each "splitting" switch, for opening the switch coordinated to the actuated push button. Preferably keyboard splitting switches K-1 to K-9 and their coordinated push buttons L-1 to L-9 constitute a mechanically interlocked system of 50 the type now commonly used in push-button tuned radio receivers. As those skilled in the art know and as it will be set forth more fully hereinafter, in a system of the described character only one push button may be actuated at any time and upon actuation of any one button, any other button which was previously actuated is automatically released.

55 In Fig. 1, with the exception of K-6, all of switches K-1 to K-9 are closed. As a result, 60 all terminals from U-1 to U-12 are electrically connected to the first output bus bar #2, whereas all of the remaining terminals U-13 to U-36 are 65 electrically connected to the second output bus bar #3. In other words, as illustrated in Fig. 1, the keyboard of the instrument is divided or "split" between the notes G₂ and A₂, the output 70 of all generators up to and including generator H₁₂ being electrically associated with output bus bar #2 and the output of all generators beyond and including H₁₃ being electrically associated with output bus bar #3.

The output signal of musical frequency currents in bus bar #2 is divided into three portions which are respectively introduced into filters 75 M-1, M-2 and M-3. These filters modify the

waveform of the input signal portions so that upon conversion into musical sounds they are capable of simulating various musical instruments, for example instruments of the string, flute or reed family. Output signal of modified character may be selectively drawn from filters M-1, M-2 and M-3 by closing one or more quality control or stop switches N-1, N-2 and N-3. The working contacts of the said switches are connected through individual decoupling resistances R to a main output bus bar 14.

The same description applies also to the output signal of musical frequency currents in bus bar 13. These are likewise divided into three portions which are respectively introduced into filters M-4, M-5 and M-6. The output signals of modified character or waveform may be selectively withdrawn from filters M-4, M-5 and M-6 by closing one or more quality control or stop switches N-4, N-5 and N-6. The working contacts of these switches are likewise connected through individual decoupling resistances R to main output bus bar 14.

The signal in the main output bus bar 14 is introduced into an amplifier O and after sufficient amplification is converted into sound in a speaker P.

From the foregoing description, the operation of the electronic organ of the invention will be readily understood by those skilled in the art. When it is desired to play a musical composition, the point where the keyboard is desired to be "split" is preset by depressing one of the push buttons L-1 to L-9. This will actuate the corresponding one of switches K-1 to K-9, which will interrupt the connection between output bus bars 12 and 13 at a point determined by the selection of the push button. Of course, the selection of the point of splitting the keyboard will be determined by the character or tonal range of the musical composition which is to be played. In Fig. 1, the point of splitting the keyboard is illustrated to be between the generators or notes G₂ and A₂. In other words, all notes below and including G₂ are assigned to output bus bar 12 and all notes above and including A₂ are assigned to output bus bar 13.

After setting the keyboard splitting point, at least one of the stop switches N-1, N-2 and N-3 and at least one of the stop switches N-4, N-5 and N-6 is closed. This will determine the musical quality or tone color imparted to the signal present in the output bus bars 12 and 13, respectively. As illustrated in Fig. 1, stop switches N-3 and N-4 are closed. Since stop switch N-3 is indicated to be representative of a reed quality and stop switch N-4 is indicated to be representative of a string quality, all notes played below G₂ will sound with a reedy quality and all notes above G₂ will sound with a string quality. Upon operating the playing keyboard and the cooperating switching keys S-1 to S-36 in accordance with requirements of a musical composition, musical oscillations from audio-frequency generators H₁ to H₃₆ will be introduced into output bus bars 12 or 13, respectively, in accordance with the frequency of the notes played being lower or higher than that of G₂ or A₂, respectively. The output signal in bus bar 12 over filter M-3 and stop switch N-3, and the output signal in bus bar 13 over filter M-4 and stop switch N-4 will be introduced into the main output bus bar 14 and then into amplifier O. The amplified oscillations of musical frequency are converted into sound in speaker P. As set

forth in the foregoing, all notes played below G₂ and generally corresponding to the accompaniment of the musical composition will sound with a reed quality and all notes played above the said note and generally corresponding to the solo or melody portion of the musical composition will sound with a string quality.

Obviously, the point of "splitting" the keyboard may be changed at any time, even during the time when a musical composition is actually being played. Thus, still assuming that the splitting point has been initially set between G₂ and A₂, as this is shown in the example selected for and illustrated in Fig. 1, it may happen that during playing a composition, in a certain passage, the accompaniment will go as high as the note C₃. In that case, all that is needed is to press button L-9 before actually reaching that particular passage. This will instantaneously open switch K-9 and at the same time will close the previously open switch K-6, thus transferring the "splitting" point by the desired degree. Of course, the said shifting of the keyboard splitting point may be resorted to as frequently as is necessary during the time a musical composition is executed.

In order to permit repeated shifting of the "splitting point" with the speed necessary for the execution of this procedure during the actual playing of a musical composition, it is necessary to incorporate certain constructional features into the switching system. First, the actuating mechanism of switches K-1 to K-9 has to be light and at the same time positive in action so that it can be actuated easily and rapidly by the operator. Second, mechanical interlocking of the several switches has to be provided so that opening of any one of the switches will automatically close all of the others. Third, the push buttons or other manually operable control elements of the switches are preferably so arranged with respect to the keys of the playing manual that their position directly indicates the point where the keyboard is "split" upon actuation of each push button. This preferred arrangement of the push buttons will be set forth more fully as the description proceeds.

The character and construction of the filter networks M-1 to M-6 will largely depend upon the waveform of the signals, delivered by the generators H₁ to H₃₆. Figs. 2 to 4 diagrammatically illustrate filters of the type that are suitable with generators producing audio-frequency oscillations of sawtooth waveform.

Fig. 2 shows a low-pass filter comprising input and output terminals 21 and 22, respectively, connected by a resistor 23 having a capacitor 24 connected across the same. Small capacitors 25 and 26 are connected between the ground and terminals 21 and 22, respectively. A filter of this type, when selecting proper circuit constants, is capable of converting sawtooth wave signals into oscillations of a waveform simulative of the tone color of string instruments.

Fig. 3 shows a low-pass filter comprising input and output terminals 31 and 32, respectively, connected by a choke coil 33. Terminals 31 and 32 are grounded through capacitors 33 and 34, respectively. A filter of this type, with a choke and capacitors of appropriate value, is suitable for converting sawtooth wave signals into oscillations of a waveform simulative of the flute or diapason qualities of an organ.

Fig. 4 shows a high-pass filter comprising input and output terminals 41 and 42, respectively, con-

nected by a capacitor 43. Terminals 41 and 42 are grounded through chokes 44 and 45, respectively. A filter of this type, with a capacitor and chokes of appropriate value, is suitable for converting sawtooth wave signals into oscillations of a waveform simulative of a reed instrument. For further details of filters of the described character reference may be had to my U. S. Patent No. 2,403,664.

Fig. 5 shows somewhat diagrammatically the construction of a preferred form of push button switch which is suitable for the purposes of the present invention. For simplicity of illustration only 3 of the 9 push button controlled switches are illustrated.

The switch essentially comprises a pair of frame plates 51 held in parallel spaced relation by bracket 52. Push rods 53, 54 and 55 are slideably mounted in frame plates 51 and are biased outwardly by means of springs 56. Each push rod is provided with a protruding portion 57 having an upper inclined edge and a lower transverse edge. These protruding portions are adapted to cooperate with a transversely displaceable latching bar 58, pressed to the left by a spring 59.

Push rods 53, 54 and 55 carry movable contactors 60, 61 and 62, respectively, separated from the body of the rods by insulation 63. Contactors 60, 61 and 62 are adapted to cooperate with pairs of stationary contacts 64, 65; 66, 67; and 68, 69, respectively. Terminal U-10 is connected to contact 64; terminal U-11 is connected to contacts 65 and 66; terminal U-12 is connected to contacts 67 and 68 and terminal U-13 is connected to contact 69. Push rods 53, 54 and 55 are provided with buttons L-4, L-5 and L-6 at their lower end for convenient manual operation. (See also Fig. 1.)

Normally, in the inoperative condition of the switch, all of the push rods are in their outwardly extending position and terminals U-10, U-11, U-12 and U-13 are all connected to each other due to the fact that each pair of stationary contacts (64, 65; 66, 67; 68, 69) is bridged over by the corresponding interposed movable contactor (60, 61, 62, respectively). However, upon actuation of one of the push rods, for example 55, contactor 62 will be displaced beyond stationary contacts 68 and 69 and the circuit will be broken between terminals U-12 and U-13, as this is illustrated in both Figs. 1 and 5. At the same time, latching bar 58 will be displaced to the right by the inclined edge of protuberance 57 against the pressure of spring plate 59. Immediately thereafter the latching bar will snap back and will prevent the push rod to be returned by its spring 56 due to locking engagement of the latching bar with the transverse portion of protuberance 57. The push rod will be retained in its "in" position until any one of the other push rods is actuated when the transverse displacement of latching bar 58 occasioned by the displacement of the push rod being actuated will release the first actuated push rod from its locked position and permits it to be returned in its original position by its compressed spring 56. Thus, it will be noted that upon actuation of any one of the push rods, the previously actuated and locked push rod is automatically released. Of course, great variations are possible in the construction of automatically interlocked push button switches of the described character and for further details of such switch constructions reference may be had, for example, to Hall et al. Patent No. 2,234,405.

Fig. 6 is a fragmentary perspective view of the

keyboard portion of an electronic organ embodying the invention. This comprises the usual manual 70 of playing keys above which are arranged stop tablets or switches N-1, N-2 and N-3 corresponding to the first "voice" of the "split" keyboard, and stop tablets N-4, N-5 and N-6 corresponding to the second "voice" or portion of the "split" keyboard. Directly underneath the playing keys are arranged the keyboard splitting switches operable by small push buttons L-1 to L-9. It will be noted that the location of these push buttons permits them to be conveniently actuated by the player even while executing a musical composition. It is also to be observed 15 that each push button is placed directly underneath the small interspace between two adjoining keys corresponding to two "natural" notes of the scale. Thus, the location of each push button directly and unmistakably indicates the point 20 where the keyboard will be "split" upon operation or depression of such button.

In the event that it is desired to provide also for "splitting" the keyboard at points between the "naturals" and the "sharps," the corresponding 25 additional push buttons may be arranged in a second row, at a level somewhat lower than that of the first one.

Although the present invention has been disclosed in connection with a few preferred embodiments thereof, variations and modifications may be resorted to by those skilled in the art without departing from the principles of the present invention. I consider all of these variations and modifications as within the true spirit and scope of the present invention, as disclosed in the foregoing description and defined by the appended claims.

What is claimed is:

1. An electrical musical instrument comprising 40 in combination a set of audio-frequency generators having output frequencies respectively corresponding to successive notes of the equally tempered musical scale, an output terminal for each of said generators, a manually operable switching key interposed between each of said generators and its corresponding output terminal adapted when actuated to render output signal from said generator effective at the corresponding terminal, a first output network permanently connected to 45 a first group of said output terminals, a second output network permanently connected to a second group of said output terminals, and switching means for selectively connecting a desired plurality of a third group of terminals to the one output network and the remainder of said third group of terminals to the other output network.

2. An electrical musical instrument comprising 50 in combination a system of generators for producing note frequency oscillations corresponding to notes of a musical scale, an output terminal for each of said generators, a manually operable switching key interposed between each of said generators and its output terminal adapted when 55 actuated to render output signal from said generator effective at its terminal, a first output network permanently connected to all output terminals up to a certain predetermined note, a second output network permanently connected to all output terminals above another predetermined note, and a range-splitting switch interposed between each pair of adjoining terminals in the intermediate range between and including the said predetermined notes, said switches being normally closed to connect the terminals in the inter-

mediate range to each other and to the said output networks and being capable of selective actuation to disconnect the said networks from each other at any desired point in the said intermediate range.

3. An electrical musical instrument comprising in combination a system of generators for producing note frequency oscillations corresponding to notes of a musical scale, an output terminal for each of said generators, a manually operable switching key interposed between each of said generators and its output terminal adapted when actuated to render output signal from the generator effective at its terminal, a low range output network connected to all output terminals up to a predetermined note, a high range output network connected to all output terminals above another predetermined note, a range-splitting switch interposed between each pair of adjoining terminals in the intermediate range between and including the said predetermined notes, said switches being normally closed to sequentially connect the terminals in the intermediate range to each other and to the said output networks and being capable of selective actuation to disconnect the said networks from each other at any desired point in the said intermediate range, and means responsive to the actuation of any one of said range-splitting switches to render the rest of said switches inoperative.

4. In an electrical musical instrument, the combination which comprises a set of sequentially arranged sources of note frequency oscillations, a primary output bus bar, a switching key interposed between each of said sources and said bus bar adapted when actuated to render signal from said sources selectively effective in said bus bar, a system of splitting switches operable to selectively split said main output bus bar into a pair of secondary bus bars at any one of a plurality of desired points, tone control means individual to said secondary output bus bars for modifying the harmonic structure of the signals present therein, and a common output circuit in which the modified signals derived from both secondary bus bars are rendered collectively effective.

5. In an electrical musical instrument, the combination which comprises a set of sequentially arranged sources of note frequency oscillations, a primary output bus bar, a switching key interposed between each of said sources and said bus bar adapted when actuated to render signal from corresponding sources effective in said bus bar, a system of splitting switches operable to selectively split said main output bus bar into a pair of secondary bus bars at any one of a plurality of points, tone control means individual to said secondary output bus bars for modifying the harmonic structure of the signals present therein, a common output circuit in which the modified signals derived from both secondary bus bars are rendered collectively effective, and an interlocking mechanism for said splitting switches whereby upon operation of any one splitting switch all of the other splitting switches are automatically disabled.

6. In an electrical musical instrument, the combination which comprises a set of sources of complex note frequency oscillations sequentially arranged in the order of increasing frequency, a terminal for each of said sources, a switching key interposed between each of said sources and its terminal, a low-range bus bar permanently con-

nected to all terminals up to a predetermined frequency, a high-range bus bar permanently connected to all terminals beyond another predetermined frequency, an intermediate range bus bar connected to the remaining terminals, a system of splitting switches operable to selectively split said intermediate range bus bar into two portions respectively connected to said low- and high-range bus bars, an output circuit, a plurality of filter networks, and a stop switch for each of said filter networks to selectively interpose said networks between the low and high range bus bars and the said output circuit.

7. In an electrical musical instrument, the combination which comprises a set of sources of note frequency oscillations, a primary output bus bar, a switch interposed between each of said sources and said bus bar adapted when actuated to render signal from corresponding sources effective in said bus bar, a playing key for each of said switches collectively constituting a playing manual, a system of splitting switches operable to selectively split said main output bus bar into a pair of secondary bus bars at any one of a plurality of points, tone control means individual to said secondary output bus bars for modifying the harmonic structure of the signals present therein, a common output circuit in which the modified signals derived from both secondary bus bars are rendered collectively effective, and manually operable elements for actuating said splitting switches, said elements being so constructed and arranged with respect to the keys of said playing manual as to directly indicate the splitting point that becomes effective upon operation of any one of said elements.

8. In an electrical musical instrument, the combination which comprises a set of sources of note frequency oscillations, a primary output bus bar, a switch interposed between each of said sources and said bus bar adapted when actuated to render signal from corresponding sources effective in said bus bar, a system of splitting switches operable to selectively split said main output bus bar into a pair of secondary bus bars at any one of a plurality of points, tone control means individual to said secondary output bus bars for modifying the harmonic structure of the signals present therein, a common output circuit in which the modified signals derived from both secondary bus bars are rendered collectively effective, an interlocking mechanism for said splitting switches whereby upon operation of any one splitting switch all of the other splitting switches are automatically disabled, and manually operable elements for actuating said splitting switches, said elements being so constructed and arranged with respect to the keys of said playing manual as to directly indicate the splitting point that becomes effective upon operation of any one of said elements.
